HOPPER CAR CONSTRUCTION

Norman B. Akitt, Troy, N. Y., assignor to Adirondack Foundries and Steel Incorporated, Watervliet, N. Y., a corporation of New York

Application December 20, 1935, Serial No. 55,488

2 Claims. (Cl. 105—253)

The present invention relates generally to railway hopper cars and particularly to door frames for the hoppers of such cars.

The railway hopper car is provided with means whereby its cargo or lading may be discharged through an aperture, or apertures, in the bottom thereof and it is now common practice to provide each such car with a plurality of hoppers or chutes, each such hopper or chute having a door or closure which, when locked or latched in sealing position, prevents egress of the cargo or lading but which, when released, permits the free discharge of the entire contents of the car. Many types of door frames and doors for the hoppers of such cars have heretofore been designed or suggested and many of such previous suggestions have been carried out in actual practice. The object of the present invention is to provide a door frame having a number of improvements over those of the prior art which improvements, while relating for the most part to details of construction, render the door frame when put into use more rigid and durable and more satisfactory in operation than the door frames heretofore employed or designed.

The improved door frame is of the unitary type, by this it being meant that the top, bottom, and side members are cast simultaneously and form a one-piece frame which may be readily applied to the car frame and hopper sheets of a railway hopper car. The various features of novelty will be hereinafter particularly pointed out.

In the drawings:

Figure 1 is a view in elevation of the novel door frame, with door attached and partly broken away, portions of a hopper car being also illustrated to show the manner of attachment of the frame thereto;

Figure 2 is a section on line 2—2 of Figure 1; Figure 3 is a section on line 3—3 of Figure 1;

Figure 4 is a section on line 4—4 of Figure 1; Figure 5 is a front elevation of a somewhat different form of the door frame;

Figure 6 is a side elevation of this door frame; Figures 7, 8, and 9 are sections on line 7—7, 8—8, and 9—9, respectively of Figure 5; and

Figure 10 is a section on line 10—10 of Figure 5 but showing also portions of a hopper car frame, the hopper door in section and certain portions of the hopper sheets also in section illustrate the manner of application of the door frame to a car.

In each form of the invention all portions of the door frame proper are formed at one time and in one piece, preferably by a casting opera-

tion. The door frame shown in Figures 1 to 4 inclusive comprises top and bottom members 10 and 11, respectively, and outer and inner side members 12 and 13, respectively. It will be understood that when the door frame is positioned upon a hopper car it lies generally transversely of the car with the outer frame member 12 toward the outer side wall of the car and the inner frame member 13 closely adjacent the main longitudinally extending structural member or center sill of the car. The upper frame member 10 varies somewhat in section from end to end, as may be seen upon an inspection of Figure 1 but at all sections is angular in cross-section, as generally shown in Figure 3. Thus it has a flat portion 15 the upper surface of which comprises a seating surface for the lower edge portion 16 of a slope sheet, such slope sheet being suitably secured to the top member 10 of the frame at various points along the length of such member. Extending at right angles to the flat portion 15 of the upper member 10 is a flange-like portion 17 which acts as a stiffening flange for imparting to this transverse member sufficient strength and rigidity to enable it to withstand the weight of the cargo within the car. The lower edge of the flat portion 15 merges with or joins an inclined or sloping portion 18 the horizontal lower edge of which defines the upper margin of the aperture provided for the escape of lading. At its inner end the inclined portion 18 is formed integrally with a triangular web 19 which web is also integral with the inner side member 13.

Formed integrally with portions 15 and 17 of the upper member 10 are the pairs of spaced, parallel, downwardly extending hinge lugs 20 the lower ends of which are provided with aligned apertures, respectively, for the reception of hinge pins 21 by means of which the door 22 is hingedly connected to the upper member for free swinging movement.

The inner side member 13 is shown in section in Figures 2 and 4 and is seen to comprise essentially three flange-like parts, part 30, disposed normally to the plane of the door frame, which is generally flat and provides means for the convenient attachment of the door frame to the inner side hopper sheet, an aligned flange-like part 31 which forms a sealing rib to cooperate with the edge of the swinging door to effect the retention of the cargo or lading, and a part 32 disposed at right angles to parts 30 and 31 and lying substantially in the plane of the door frame,

it being the function of this part to stiffen the frame.

The stiffening part 32 lies entirely without the elongated flat member comprising parts 39 and 31 and, at the upper end of the side member 13, the web 19 and stiffening part 32 are disposed in the same plane, as shown more clearly in Figure 2.

The bottom frame member 11 is shown in section in Figure 3 and will be seen to also have attachment, sealing and stiffening parts, indicated at 25, 26 and 27, the sealing part or rib 26 being slightly off-set upwardly, however, from the attachment part 25 in order that the upper surface of this rib will be in substantial alignment with the upper surface of the slope sheet 28 of the hopper, to permit free flow of lading through the door frame when the cargo is released.

The outer side member 12 in reality comprises only a sealing flange 33 and stiffening part or flange 34, having no sheet attachment flange. The stiffening flange 34 likewise functions as a cargo retaining flange or plate, this plate being of generally triangular shape and having along its outer edge the inclined hopper sheet attachment flange 35, the entire door frame being thus generally trapezoidal in front elevation although the aperture defined thereby for the discharge of lading is rectangular. The door is indicated at 22 and may be formed in various ways, although it is preferably a cast door in which the upwardly projecting hinge lugs 37 for the reception of the hinge pins 21 are formed at the upper ends of raised, ribs 38, formed on two of the raised panels 36, thus providing a door of great strength adjacent the hinge lugs, one which may be readily fabricated and which is thoroughly efficient in action.

The top, bottom and side members of the frame are all rigidly secured to the lower margins of the respective hopper sheets and the frame is largely supported from the hopper sheets. The inner end of the top frame member 10, however, extends over the lower flange 39 of the longitudinally extending beam 40, forming one of the two main members of the center sill and is riveted to the vertically extending web of this member. It will be understood that the center line of the hopper car is indicated by the chain line 41 and that a similar hopper frame and door are disposed upon the opposite side of the center sill. A transverse beam 42 extending transversely of the car is secured to both doors adjacent their lower or free edges so that the doors on opposite sides of the center sill are constrained to move simultaneously. Means is provided for latching the doors in closed position, such means preferably comprising a latch mechanism diagrammatically illustrated at 43, which mechanism includes a latch for engaging the outer end of the beam 42 which extends beyond the outer side member 12 of the frame. This latching mechanism may be of conventional form.

In the form of the invention illustrated in Figures 5 to 10 inclusive the various parts of the frame member are generally similar to the corresponding parts of the first form of the invention but in this form of frame it is intended that the inner frame member 50 shall be attached to a flat face of the car center sill which, for instance, may be the flat face 51, disposed in vertical plane, of the channel member 52. For that rea-

son the inner side member 50 is provided with a flange 53 at its upper end adapted to lie flat against the web of the channel member 52 and to be attached thereto by rivets. The hopper sheet attachment flange 54 of the inner side member 50 lies on the opposite side of the stiffening web 55 of this member from the flange 53. It will be noted from Figure 7 that the stiffening web 55, which lies intermediate the attachment flange 54 and the sealing rib of flange 56, is inclined to the plane of the door frame and this inclination is made as great as is possible for the purpose of facilitating the flow of lading through the door frame, without, however, at the same time materially reducing its stiffening functions or unduly increasing it in thickness and weight.

The bottom member 57 of this form of frame is substantially identical with that of the former frame previously described and likewise the outer side frame member 58 corresponds in all substantial particulars with the side frame member 12 of the door frame shown in Figures 1 to 4. The top frame member 59 is also generally similar, comprising a member which is angular in cross-section from end to end. For the convenient attachment of the inclined hopper sheet 60, however, in such manner that the lower margin or edge of this sheet may lie in the same plane as the main portion thereof, the sheet attachment portion 61 has its upper flat surface inclined to the plane of the door frame. Again, the lower marginal portion 62 of the upper frame member is disposed in the plane of the door instead of at an inclination thereto, as in the case of the first form of the invention. The hopper door is indicated at 63 and is sustained by hinges in the same manner as shown in Figures 1 to 4.

Having thus described the invention, what is claimed as new and desired to be secured by Letters Patent is:

1. A door frame for a hopper car comprising top, bottom, and inner and outer side members, said members together forming an integral structure defining an aperture for the discharge of lading, the top member having a flat surface parallel to the general plane of the frame to facilitate attachment of a hopper sheet, a surface outwardly inclined toward the plane of said door opening and merging with said flat surface, the free edge of said inclined surface comprising the upper margin of the discharge aperture, and at least one of the side members having a stiffening flange in a plane parallel to said flat surface, a web connecting the free edge of said inclined surface to said side member and lying in the same plane as said stiffening flange.

2. A door frame for a hopper car comprising top, bottom, and inner and outer side members, said members together form an integral structure defining an aperture for the discharge of lading, the inner side member having sealing and sheet attachment flanges disposed in spaced parallel planes normal to the general plane of the door frame and extending substantially to the lower edge of said frame, and an interconnecting web outwardly inclined toward the plane of the door frame, to an extent which will effectively prevent the obstruction of the flow of the lading during discharge thereof.

NORMAN B. AKITT. 70
